UNITED STATES PATENT OFFICE.

JAMES FRANCIS EDDY, OF LANSDOWNE, PENNSYLVANIA.

DAILY-DATE SIGN.

1,153,545.

Specification of Letters Patent. Patented Sept. 14, 1915.

Application filed October 17, 1913. Serial No. 795,624.

To all whom it may concern:

Be it known that I, JAMES FRANCIS EDDY, a citizen of the United States and a resident of Lansdowne, in the county of Delaware and State of Pennsylvania, have invented 5 certain Improvements in Daily-Date Signs, of which the following is a specification.

The invention relates more particularly to daily date signs such as shown and described in my co-pending applications Serial No. 754,676 filed March 17, 1913, and Serial No. 779,254 filed July 16, 1913, and the objects of this invention are to so connect the pad of a daily date sign to its back that the 15 same cannot be readily removed until the pad is used up; to provide such means which can be applied to a daily date sign the back of which is retained permanently by the user and new pads obtained as needed; to discourage the discarding of the back with its 20 advertising, since the back and pad are not readily separated; to provide for the ready removal of the cap when the pad is exhausted; to allow for the convenient application 25 of the pad and cap into locked position upon the back; to enable the cap to be supported with increased rigidity upon the back; to secure a simple, inexpensive and effective construction, and to obtain other advantages and results as may be brought out in 30 the following description.

Referring to the accompanying drawings, in which like numerals of reference indicate the same parts throughout the several views, 35 Figure 1 is a perspective view of a daily date sign embodying my invention, but having the pad leaves removed in order to disclose the construction and application of the cap to the back; Fig. 2 is a perspective view of 40 the rear of said cap detached from the back and having the pad leaves mounted in place; Fig. 3 is a cross-sectional view on line A—A of Fig. 1, showing the pad carried by the cap, and Figs. 4 and 5 are two forms of 45 backs to which the invention may be applied.

In the specific embodiment of the invention illustrated in said drawings, the reference numeral 1 indicates a back to which the invention is applied, said back being provided with pad-supporting means. The specific construction of said supporting means is immaterial to the present invention, but for purposes of illustration I have shown in Figs. 1, 3 and 4, a back comprising 55 a mount 2 with a head-plate 3 supported upon the upper portion thereof, said plate

3 having adjacent its lower edge and substantially parallel thereto, a slot 4 terminating short of the side edges of the head-plate. This slot is preferably formed by making a 60 slit, without the removal of any of the material of which the head-plate is composed, and bending the lower lip or margin 5 of said slit forwardly outward, as shown, so that an upwardly open slot is formed. The 65 upper part of the head-plate preferably carries upon its face advertising matter of a permanent character.

In Fig. 5 I have shown, instead of the slot in a head-plate, a hanger strip 6, preferably 70 stamped out of sheet metal and formed at its ends into feet 7, 7, which are slightly offset from the plane of the middle main portion 8, so that when they are secured, as by screws 9, 9, to a mount 10, a slot 11 is 75 formed between said mount and the middle main portion 8 of the strip, as shown. In this particular instance I have shown advertising matter applied directly upon the upper portion of the mount 10, and no head- 80 plate employed, but obviously the hanger strip could be secured upon the lower edge of a head-plate, if desired, or in fact any suitable construction adapted to the purpose of the present invention may be employed 85 without departing from the spirit or scope of the invention.

The particular feature of the present invention resides in the means or cap for supporting the leaves of the pad upon the back, 90 and shown in Figs. 1 to 3. In carrying out my invention, I bend from sheet metal a cap 12 having a top portion 13 broad enough and long enough to cover the upper ends of the leaves of a pad 14. The metal comprising 95 said cap is bent downwardly along both of the longitudinal edges of the top portion 13, thereby forming front and rear flanges 15 and 16 respectively. Ears 17, 17 at the front, and 18, 18 at the rear, one pair at 100 each end of the cap and forming downward extensions of the said flanges, overlap the leaves of the pad adjacent the side edges thereof, and support said leaves by transverse pins passing between the front and 105 rear ears.

Between the two rear ears 18, 18, a tongue 22 on the rear flange 16 depends lower than said ears and is separated from them by vertical slits 20, 20, the distance between said 110 slits being governed by the length of the slot of the back which is to support the pad.

The proportion of one to the other is such that the tongue 22 between the slits 20, 20 will readily enter the slot, whereas the ears 18, 18 rest against the front of the back on portions thereof which do not project forward from the general plane of the back, as shown in Fig. 1. In this manner it will be seen that the tongue 22 and ears 18, 18 will wedgingly grip the lower lip of the slot and provide a rigid support for the cap upon the back.

In order to prevent too ready or inadvertent removal of the cap from the back, I have provided detents projecting from the tongue 22 toward the front flange 15 and so positioned as to lie below the bottom edge of the member forming the slot for the tongue, (whether head-plate or hanger strip or otherwise), and engage said edge when any attempt is made to remove the pad. The particular embodiment herein disclosed for such detents is a tapered spur 21 stamped out of the sheet metal tongue, and readily obtained by making a V-shaped slit with the point directed upward and then bending said spur out of the plane of the metal into inclined relation thereto. In applying the cap to the back, the inclined surfaces of these spurs slide readily behind the lower lip of the slot as the tongue 22 is hooked into said slot, and the spurs spring outward again beneath said lip so as to catch thereon if any attempt is made to slide the pad up again to detach it. The pad is thus quite effectively locked to the back, in place for use therewith, and especially so because the leaves of the pad prevent a clear vision of, or ready access to, said spurs in their engaged relation to the back. The pad therefore is not likely to be separated from the backing, either inadvertently or otherwise, and so the back with its advertising is preserved and displayed in connection with the useful pad.

When all the leaves of the pad have been torn off, it is then very convenient to bend back or flatten the spurs 21, either with the finger or any convenient instrument, so that they will pass behind the lip and the cap can be readily removed from the back of the sign or calendar. This cap is then thrown away and the back is all ready to receive the new pad with its spurred cap.

Having thus described the invention, what I claim is:—

1. The herein-described pad for daily date signs, comprising in combination with a plurality of leaves, a cap having opposite parallel flanges one in front of said leaves and the other behind them and an intermediate portion at the top edges of said leaves holding said flanges in spaced relation, said flanges including pairs of opposite ears at the ends of the cap and the rear flange in-

cluding a depending tongue between the ears and separated therefrom, said tongue being adapted to hook over a strip or the like while said ears lie against its front, and cross-pins extending one through the opposite ears of each pair and the leaves of the pad so as to connect the cap flanges and support the leaves while leaving the tongue free to be exposed for entering a supporting slot by flexing the leaves.

2. The herein-described pad for daily date signs, comprising in combination with a plurality of leaves, a cap having opposite parallel flanges one in front of said leaves and the other behind them and an intermediate portion at the top edges of said leaves holding said flanges in spaced relation, cross-pins extending through said cap flanges and leaves adjacent the opposite ends thereof connecting said flanges and supporting said leaves, the rear flange of the cap including a depending tongue intermediate said cross-pins substantially in the plane of the flange and adapted to be exposed for entering a supporting slot by flexing the leaves, and resilient spurs on said tongue normally projecting inward toward said leaves and upward toward the body of the cap and adapted to project beneath a wall of said supporting slot when the tongue is inserted therein and prevent inadvertent escape of said tongue therefrom.

3. The herein-described pad for daily date signs, comprising in combination with a plurality of leaves, a cap having opposite parallel flanges one in front of said leaves and the other behind them and an intermediate portion at the top edges of said leaves holding said flanges in spaced relation, the rear flange including ears depending from its lower edge adjacent its opposite ends, cross-pins extending through said ears and front flange and leaves for connecting said flange and ears and supporting said leaves, the rear flange also including a tongue depending from its lower edge between said ears separate therefrom and depending further than said ears, said tongue being substantially in the plane of the flange and adapted to be exposed for entering a supporting slot by flexing the leaves and ears, and resilient spurs near the free edge of said tongue normally projecting inward toward the leaves and upward toward the body of the cap and adapted to project beneath a wall of said supporting slot when the tongue is inserted therein.
